CLAIM

The ornamental design for a towel warmer bucket, as shown and described.

DESCRIPTION

FIG. 1 is a front, left and top perspective view of a first embodiment of a towel warmer bucket, showing our new design;

FIG. 2 is a rear, left and bottom perspective view thereof; FIG. 3 is a perspective view in an opening state of FIG. 1; FIG. 4 is a front view thereof;

FIG. 5 is a rear view thereof;

FIG. 6 is a left side view thereof;

FIG. 7 is a right side view thereof;

FIG. 8 is a top plan view thereof; and,

FIG. 9 is a bottom plan view thereof.

The broken lines shown in the drawings illustrate portions of the towel warmer bucket that form no part of the claimed design.
